UNITED STATES PATENT OFFICE.

CHARLES E. GREGORY, OF NEW ROCHELLE, NEW YORK, ASSIGNOR OF ONE-HALF TO
RICHARD E. TURNER, OF AMSTERDAM, NEW YORK.

VENEER BARREL.

1,168,391.

Specification of Letters Patent. Patented Jan. 18, 1916.

Application filed April 14, 1914. Serial No. 831,825.

To all whom it may concern:

Be it known that I, CHARLES E. GREGORY, a citizen of the United States, residing at New Rochelle, in the county of Westchester 5 and State of New York, have invented a new and useful Veneer Barrel, of which the following is a specification.

The invention relates to improvements in veneer barrels.

10 The object of the present invention is to improve the construction of veneer barrels and to provide a simple, inexpensive, and practical non-sifting veneer barrel, adapted to be shipped in a knocked-down condition, 15 and capable of having its parts readily assembled without necessitating skilled labor.

20 A further object of the invention is to provide a non-shrinking or swelling veneer barrel of this character, having expandable ends 25 adapted to permit the barrel heads to be readily applied to and removed from the barrel, so that the latter will not require re-coopering.

With these and other objects in view the 30 invention consists in the novel construction and combination of parts hereinafter fully described, illustrated in the accompanying drawings, and pointed out in the claims hereto appended, it being understood that 35 various changes in the form, size, proportion and minor details of construction, within the scope of the claims, may be resorted to without departing from the spirit or sacrificing any of the advantages of the invention.

In the drawings:—Figure 1 is an elevation of a veneer barrel constructed in accordance with this invention. Fig. 2 is a central vertical sectional view of the same. 40 Fig. 3 is an enlarged horizontal sectional view of a portion of the barrel. Fig. 4 is a perspective view of one of the stave sections or panels of the barrel, partly broken away to illustrate the arrangement of the grain of 45 the veneer. Fig. 5 is a perspective view of one of the metallic joint strips. Fig. 6 is an enlarged detail sectional view of one of the joints of the barrel.

Like numerals of reference designate corresponding parts in all the figures of the drawings.

In the accompanying drawings, in which is illustrated the preferred embodiment of the invention, the body of the barrel consists 55 of a plurality of veneer units or stave sec-

tions 1 extending longitudinally of the barrel throughout the entire length of the same, and connected by longitudinal metallic joint strips 2 provided with grooves or channels 3 loosely receiving the side edges 4 of the 60 veneer units or panels. Two, three, or four veneer units or stave sections 1 are preferably employed in the construction of the barrels which may be employed for handling various commodities and materials, such as 65 sugar, flour, cement, etc., as the metallic joint strips provide an absolutely tight non-sifting barrel. Each veneer unit or section is preferably composed of three layers of veneer 5, 6, and 7, with the grain of the central or intermediate layer 6 arranged at 70 right angles to the grain of the inner and outer layers 5 and 7, but the number of layers may, of course, be varied. Also, if desired, a layer of fiber board may be employed with one or more layers of veneer, or other suitable material may be used in the construction of the stave sections. The 75 layers or thicknesses of the veneer panel are secured together by adhesive material, such as glue, cement, or the like, and the bilge is formed in the veneer section or unit by expanding the fiber of the veneer prior to the 80 hardening of the adhesive material. It has been found in practice that barrels may be 85 constructed in this manner with a diameter at the center five inches greater than at the 90 ends of the barrel.

The metallic joint strips are constructed of a single piece of sheet metal or other suitable material, which is bent or folded longitudinally at points equidistant of the central or median line of the strip 2 to form 95 relatively stiff outer flanges 8 of two-ply or thicknesses, and the metal is then bent longitudinally at right angles to form an inwardly extending web 9 of two-ply or thicknesses of a length corresponding to the thickness of the veneer units or stave sections 1. The free side portions 10 of the metal are curved in opposite directions and diverge, as clearly shown in Fig. 5 of the drawings, prior to assembling the parts of a barrel, the open inner wings or flanges 10 facilitating the ready introduction of the 100 side edges of the stave sections in the spaces between the outer and inner flanges 8 and 10. After the stave sections have been assembled, the inner flanges 10 are bent 105 against the inner faces of the said stave sec-

tions, and in substantial parallelism with the outer flanges 8 to form the channels 3. By constructing the inner flanges 10 of the terminal side portions of the sheet metal, 5 said side flanges consist of a single thickness of metal and are flexible and adapted to be readily bent into their finished or engaging position. After the inner flanges have been bent against the inner faces of the veneer 10 units or stave sections, the quarter or bilge hoops 11 are applied and securely retain the stave sections in their interlocked relation with the joint strips. Any number of hoops 11 may, of course, be employed.

15 The joint strips slidably receive the side edges of the stave sections and the ends of the body of the barrel beyond the intermediate hoops 11 are expansible and the stave sections are adapted to slide outwardly and 20 inwardly in the channels of the joint strips with respect to the central web portions 5. This will enable the heads 12 of the barrel to be readily sprung into and out of engagement with the crozes or grooves 13 of head 25 receiving strips 14. By this construction the barrels require no recoopering and may be used repeatedly. The head receiving strips 14, which may be constructed of any suitable material, are preferably made of 30 two-ply veneer, and they are secured to the inner faces of the stave sections by nails, staples, or other suitable fastening devices. Also, the head receiving strips reinforce and strengthen the stave sections and prevent 35 the same from splitting. The stave receiving strips are preferably beveled at their inner faces and the croze or groove is also designed to be V-shaped to fit the oppositely beveled edges of the barrel head 12. The ex- 40 pansible ends of the body of the barrel are rigidly maintained in engagement with the heads by end hoops 15, secured on the ends of the barrel by nails or other suitable fastening devices and preferably provided at 45 their outer edges with reinforcing beads 16. When the end hoop is detached, the end of the barrel may be expanded, and the head readily removed from the groove 13. The barrel may be shipped in a knocked-down 50 condition, so as to receive low freight rates, and the parts may be readily assembled by unskilled labor. Also, as the joint strips form overlapping joints at each of the side edges of each stave section, a perfectly tight, 55 non-sifting barrel is assured. While the improvement is particularly adapted for barrels, it may be applied to the construction of various other receptacles of veneer or other suitable material.

60 What is claimed is:

1. A receptacle having a bilge and including a plurality of tapered stave sections, and longitudinal joint strips located between the side edges of the stave sections 65 and overlapping each of the side edges of

each stave, said joint strips permitting relative lateral movement of the tapered ends of the stave sections to expand and contract the end of the receptacle to permit the head of the same to be removed and replaced without 70 recoopering.

2. A receptacle having a bilge and including tapered stave sections, longitudinal joint strips interposed between the adjacent edges of the stave sections and receiving the side 75 edges thereof and permitting relative sliding movement of the tapered ends of the stave sections to expand and contract the end of the receptacle to permit the head thereof to be removed and replaced without 80 recoopering, said strips overlapping the outer faces of the staves at the points to provide a non-sifting barrel.

3. A receptacle having a bilge and including a plurality of tapered stave sections, 85 and joint strips having grooves or channels receiving the side edges of the stave sections and permitting relative lateral movement of the tapered ends of the stave sections to expand and contract the end of 90 the receptacle to permit the head thereof to be removed and replaced without recoopering.

4. A receptacle having a bilge and including tapered stave sections, and joint strips 95 provided with spaced flanges arranged in pairs and forming channels which receive the side edges of the stave sections and permit relative lateral movement of the tapered ends thereof to expand and contract the end 100 of the receptacle and enable the head thereof to be removed and replaced without recoopering, the flanges at one of the faces of the stave sections being relatively flexible to enable them to be bent into engagement 105 with the stave sections after the parts have been assembled.

5. A receptacle having a bilge and including tapered stave sections, and joint strips provided with spaced flanges arranged in 110 pairs and forming channels which receive the side edges of the stave sections and permit relative lateral movement of the tapered ends thereof to expand and contract the end of the receptacle and enable the head thereof to be removed and replaced without 115 recoopering, the flanges at the outer faces of the stave sections being relatively stiff and the other flanges being relatively flexible to enable them to be readily bent against the 120 said stave sections after the parts have been assembled.

6. A receptacle having a bilge and including a plurality of tapered stave sections, longitudinally channelled joint strips interposed between and receiving the side edges of the stave sections and overlapping said edges both inside and outside, and intermediate hoops embracing the receptacle between the ends thereof and maintaining the 125 130

stave sections in interlocked relation with the joint strips, the latter permitting relative lateral movement of the tapered ends of the staves to expand and contract the ends 5 of the barrel to permit the heads thereof to be removed and replaced without recoopering.

7. A receptacle having a bilge and provided with tapered stave sections, the latter 10 having head receiving grooves at their ends, intermediate and end hoops embracing the staves, heads fitted in the grooves of the staves, and means for loosely connecting the staves at the side edges thereof to permit 15 relative lateral movement of the ends of the stave sections when the end hoops are detached, whereby the ends of the receptacle may be expanded and contracted to remove and replace the heads without recoopering, 20 said means overlapping the side edges of the staves at the joints to prevent material from sifting therethrough.

8. A receptacle having a bilge and including a plurality of veneer stave sections pro-

vided at their ends with head receiving 25 strips having grooves, longitudinal joint strips having channels receiving the side edges of the stave sections, intermediate hoops maintaining the intermediate portions 30 of the stave sections in rigid relation with the joint strips, and detachable end hoops arranged on the ends of the receptacle and normally holding the ends of the staves in rigid relation with the joint strips, 35 the latter permitting relative lateral movement of the ends of the staves when the end hoops are detached to expand and contract the receptacle to permit the heads thereof to be removed and replaced without re- 40 coopering.

In testimony, that I claim the foregoing as my own, I have hereto affixed my signature in the presence of two witnesses.

CHARLES E. GREGORY.
